FLUID FUEL BURNER FOR DOMESTIC HEATING PURPOSES

Application filed September 26, 1929. Serial No. 395,242.

This invention relates to improvements in fluid fuel burners for domestic heating purposes and more particularly to a mechanism of this type which embodies flameless oxidation of the fuel preparatory to combustion thereof.

While it has always been the aim of fluid fuel burners for domestic heating purposes to produce a combustion so nearly complete that no soot nor smoke results from the flame of the burner to clog or pass through the furnace and chimney, it has been found that in order to approach this condition it has been necessary to sacrifice the heat producing effects of the burner. It is an object of this invention by the application of flameless oxidation of the fuel preparatory to combustion to produce practically a smokeless flame without reducing the efficiency of the burner.

With these and other objects in view reference is made to the accompanying sheets of drawings which illustrate a preferred form of this invention with the understanding that minor detail changes may be made therein without departing from the scope thereof.

In the drawings:

Figure 1 is a fragmentary view of the lower portion of a domestic heating furnace illustrating in side elevation the application of this improved device associated therewith.

Figure 2 is a top plan view of Figure 1 with parts broken away.

Figure 3 is a view partly in side elevation, with parts broken away, and partly in vertical section taken on the line 3-3 of Figure 2, looking in the direction of the arrows.

Figure 4 is a view in vertical section taken on the line 4-4 of Figure 3 looking in the direction of the arrows.

Figure 5 is an enlarged detail view in rear elevation, with parts broken away, of the exterior of the fuel nozzle casing.

Figure 6 is a view in vertical section of the fuel nozzle casing taken on the line 6-6 of Figure 5.

The embodiment of this invention as illustrated upon the drawings, includes a rectangular casing 1, supported against the exterior of the furnace or heater 2 having a semi-circular casing 3 projecting from the lower por-

tion of the rectangular casing through an opening provided therefor in the furnace wall and extending within the interior of the fire box or combustion chamber of the furnace. The rectangular exterior casing 1 is lined throughout with any commercial high temperature refractory material and is provided on the top near the front edge with an opening 4, preferably provided with a mica or non-heat conducting transparent closure, whereby the interior of the casing may be inspected to determine whether or not a flame is existing therein. The top of the casing preferably adjacent the rear edge contiguous to the exterior furnace wall 2 is provided with an air intake 5 preferably in the form of a tubular member extending above and below the top of the casing with the interior portion surrounded by the same commercial high temperature refractory material as the interior of the casing and the exterior portion provided with a damper 6 manually regulated by the handle 6 for regulating the amount of air passing therethrough.

The semi-circular casing 3 within the combustion chamber is preferably of greater width than the exterior casing 1 with the center line of its curved surface in prolongation of the bottom of the casing 1 to which it is joined with the extremities of the curved surfaces terminated in a horizontal plane, as shown in Figure 4. The interior of the curved surface as well as its end closure 7, is lined with the same commercial high temperature refractory material as the interior of the casing 1, and forms in effect an elongated semi-circular trough, open at the top, extending in prolongation of the rectangular casing into the interior of the fire-box or combustion chamber of the heater. Adjacent the bottom of this semi-circular trough is arranged a tubular member 8 the axis of which is arranged at right angles to the vertical center line of the casing 1 and is joined to and opens through the rear wall of said casing while the other end is joined to and closed by the rear wall 7 of the semi-cylindrical member 3. This tubular member 8 is lined with the same commercial high temperature refractory material as the interior of the

member 3 and casing 1 as well as the closed end thereof.

Arranged within the tubular member 8 and resting upon the bottom of the refractory lining thereof is a pipe or tube 9, formed of the same commercial high temperature refractory material as the lining of the members 3, 8 and casing 1. This tube 9 extends within the interior of the casing 1 and is 10 terminated short of the closure formed by the refractory lining at the end of the member 8 whereby a passage is formed therebetween. This member 9 is of less exterior diameter than the interior diameter of the 15 refractory lining of the member 8, thereby allowing a passageway between the exterior of the member 9 and the interior of the member 8 which is in communication with the interior of the tube 9 through the passageway 20 at the exterior end of the member 8. As heretofore stated the tubular member 9 enters within the interior of the casing 1 and this end opens through and is joined to a vertical partition 10 of the same commercial high 25 temperature refractory material as the said member 9. This partition terminates above the horizontal center of the casing 1 and is preferably carried back to join the refractory lining of the rear wall of said casing to form 30 a passageway connecting the space between members 8 and 9 and the interior of the casing 1 which passageway is preferably of cylindrical form, composed entirely of the same commercial high temperature refrac- 35 tory material as the member 9 and lining of member 8 and is provided near its opening into the casing 1 with a damper 11, adapted to be manually operated by the handle 12 upon the exterior of the casing 1.

40 On the exterior of the front of the casing 1 and in axial alignment with the refractory tubular member 9 is arranged a cylindrical fuel nozzle casing 13 opening into the interior of the casing 1 with the exterior closure 45 supporting a fuel nozzle 15. About the cylindrical sides of the casing 13, a plurality of equally distant ports are arranged in a vertical plane which ports are adapted to communicate with the exterior atmosphere.

50 Within the casing 13 is arranged a rotatable sleeve having corresponding ports therein which sleeve is adapted to be rotated by the handle 14 and guided by a pin 14^a extending upward through a slot in the casing whereby 55 the size of the ports communicating with the atmosphere may be regulated by the rotation of said sleeve. The nozzle includes a chamber block 15^a rotatably mounted in the outer end closure of the casing 13. The chamber 60 within the block communicates at its outer end with a steam pipe 16 hereinafter described with the other end of the chamber supporting and engaging an elongated hollow steam nozzle 17 extending axially of the 65 chamber 13 in the direction of the interior

of the casing 1. The nozzle block is joined to a tubular extension 18 of greater interior diameter than the exterior of the steam nozzle which is tapered and its apex provided with an aperture in axial alignment with the bore of the steam nozzle. The nozzle block 15 is provided with a port communicating with the interior of this member and with a pipe 19 leading to a source of liquid fuel supply, not shown.

70 A U-shaped steam pipe is provided with the ends of its parallel arms 20 secured to the exterior sides of the casing 1, which arms extend through the wall of the furnace 2 and over the open refractory lined semi-circular trough 3 and are supported upon the rear closure 7 thereof with the bottom 21 of the U extending therebeyond. The free open 75 ends of each arm are provided with closures 22 and 23 preferably extending beyond the front of the cylindrical casing 1. One of these closures 23 mounts a water spray nozzle 24 which is connected to one side of a water pressure regulator 25, the other side of which is connected by a pipe 26 to a source of water supply, not shown, and the connection between the water pressure regulator and the water nozzle is preferably provided with a water pressure gauge 27 and with a manually operable valve 28. The closure 22 of the other end of the U-shaped pipe is connected to the steam pipe 16 communicating with the nozzle block and is also preferably provided with a steam gauge 29.

80 The tubular casing 8 and refractory lining thereof is provided with a plurality of oppositely disposed and equally spaced apart burner apertures 30 arranged in the horizontal plane passing through the center of said member and also with another series of oppositely disposed equally spaced apart burner apertures 31 preferably lying in the horizontal plane passing through the center of the vertical radius of the member 8 above its center.

85 The water issuing from the spray nozzle 24 is quickly converted into steam in the pipes 20 and 21 by the heat of the ignited gases issuing from burner holes 30 and 31 and this steam passing through the steam nozzle 17, unites with the oil in the surrounding member 18 and produces a spray of oil atomized by steam which is directed through the chamber formed by the partition 10 to enter the tubular member 9 of refractory material and at the same time induces air through the air ports in the casing 13, which unites with the spray of oil atomized by steam to form a combustible mixture, which mixture at first is ignited and burns within the tubular member 9, increasing the temperature of the refractory material. This flame burns or smothers out and the products of combustion and unburned vapors pass through the remainder of the heated refractory tube 9 and into the 90

larger member 8, increasing the temperature of the refractory lining thereof. Part of these products of combustion and unburned vapors pass through the burner apertures 30 and 31, mix with the atmospheric air within the semi-circular trough 3 and burn as illustrated in Figure 4, the temperature of the refractory lining of the semi-circular trough 3 also being increased by the heat from these flames. Part of the products of combustion and unburned vapors pass through the member 8 into the vertical conduit formed by the partition 10 in the rectangular casing 1 where they mingle with the incoming current of air 10 passing through the intake 5 and are ignited from the flame of the atomized oil and burn in the passageway between the partition 10 and front of the rectangular casing 1. This flame smothers out above the entrance to the 15 tubular member 9, so that the spray of oil atomized by the steam, the induced air from the nozzle casing and the products of combustion and unburned vapors from the vertical chamber all pass through the small tubular member 9 as vapor, then the vapor 20 passes through the surrounding member 8, and that part which passes through the burner apertures 30 and 31 burn in the outside air.

The refractory lining of the casing 1, the 30 refractory partition forming the vertical refractory conduit 10, the refractory linings of the members 8 and 3, and the refractory body of the tubular member 9 all are brought to a red heat. The oil atomized by the steam becomes vaporized by the high temperature within the tubular member 9, and the air induced with the spray by the high temperature causes a flameless oxidation of the oil vapors in passing through the tubular member 9 and generates heat within the refractory material forming the member 9 and lining member 8. The products of combustion in the vertical passageway between the partition 10 and front of the casing 1 above the 35 oil and steam nozzle have a triple function, namely, afford heat for vaporizing the oil, furnish carbon dioxide and water vapor to reduce free carbon deposited from the oil to carbon monoxide, and smother out the flame 40 at the burner nozzle, thereby permitting flameless oxidation and producing a cracking process of the oil in the oil vapor.

When oil is cracked in the member 9 the result is free carbon and combustible vapors 45 and this carbon is dissipated by chemical reaction with the steam from nozzle 17 and the products of combustion from the vertical chamber as follows:

The results of these reactions are combustible gases which pass through the burner apertures 30 and 31 and burn in the surrounding atmospheric air.

In starting the operation of the apparatus, it is preferable to supply steam from an independent source to enter the pipe 20 adjacent the water spray nozzle 24 and to ignite the combustible mixture in the entrance of the refractory tubular member 9 in any desired manner, and thereafter ignite the combustible gases passing through the apertures 30 and 31. After this ignition has been effected the flames playing upon the pipes 20 will produce sufficient heat to reduce the water spray to steam and the steam from the independent source may be discontinued. By the proper manipulation of the valve 28 in the water supply pipe and the similar valve 28^a in the oil supply pipe, as well as the dampers in the intake 5 and vertical conduit behind the partition 10, and by the regulation of the openings in the nozzle casing 13, the proper proportions of steam, oil, air and products of combustion may be regulated to produce the desired flames at the burner apertures 30 and 31.

What I claim is:

1. In a fluid fuel burner, the combination with means for supplying air, liquid fuel and steam thereto the said air being supplied continuously, of means for atomizing the liquid fuel in the presence of steam, means for producing flameless oxidation of the atomized fuel and for burning the vapors thereof including a refractory chamber for receiving the atomized fuel adapted to be ignited in the entrance thereof, said chamber provided with means for delivering a part of the products of combustion and unburned vapors therefrom to be burned in the atmosphere and delivering the remaining to mix with the air and be ignited and directing the products of such combustion and unburned vapors to enter the refractory chamber with the steam and atomized oil.

2. In a liquid fuel burner, the combination with means for supplying air, liquid fuel and steam thereto the said air being supplied continuously, of means for atomizing the liquid fuel in the presence of steam, means for producing flameless oxidation of the liquid fuel so atomized and for burning the vapors therefrom including a refractory chamber for receiving the atomized fuel adapted to be ignited in the entrance thereof, said chamber provided with means for delivering a part of the products of combustion and unburned vapors thereof to be burned in the atmosphere and delivering the remaining to mix with the air and be ignited and directing the products of such combustion and unburned vapors to enter the refractory chamber with the steam and atomized oil, together with means cooperating with the part of the vapors delivered for burning for producing the steam.

3. In a fluid fuel burner, the combination with means for supplying air, water and liq-

- uid fuel thereto the said air being supplied continuously, of means cooperating therewith to convert the water to produce steam, means to atomize the liquid fuel in the presence of 5 the steam, means to produce flameless oxidation of the atomized fuel including a refractory chamber to receive the atomized fuel adapted to be ignited at the entrance thereof, said chamber divided to lead part of the 10 products of combustion and unburned vapors to mix with air be ignited from the flame of the atomized fuel and lead the results of such combustion to enter the refractory chamber with the atomized fuel to smother out the 15 flame thereof and produce flameless oxidation of the fuel in said chamber, said chamber leading a part of such vapors to burner aperture to be burned in the surrounding atmosphere.
- 20 4. In a fluid fuel burner, the combination with means for supplying air, water and liquid fuel thereto the said air being supplied continuously, of means cooperating therewith to convert the water to produce steam, means 25 to atomize the liquid fuel in the presence of the steam, means to produce flameless oxidation of the atomized fuel including a refractory chamber to receive the atomized fuel adapted to be ignited at the entrance thereof, 30 said chamber divided to lead part of the products of combustion and unburned vapors to mix with air supplied thereto to form a combustible mixture to be ignited from the flame of the atomized fuel and lead the results 35 of such combustion to enter the refractory chamber with the atomized fuel, smother out the flame thereof and produce flameless oxidation of the fuel in said chamber, said chamber leading a part of such vapors to 40 burner aperture to be burned in the surrounding atmosphere and actuate the steam producing means.
5. In a fluid fuel burner for heating purposes, the combination with the combustion 45 chamber of a heater of a refractory trough open at the top and entering thereinto, a refractory casing arranged on the exterior of the combustion chamber, a refractory tubular member adjacent the bottom of the trough 50 communicating at one end with the casing and closed at the other, a plurality of burner apertures provided upon the upper side of said member, a smaller refractory tube arranged within the said tubular member, 55 spaced apart from the closed end thereof and extending within and opening into the exterior casing, a refractory partition in said casing joining said entering end of said smaller tube forming a passage from the open end of 60 the large tubular member to adjacent the top of the exterior casing, an air inlet arranged in said casing above said passage, a casing entering the exterior wall of the refractory casing opposite the opening of the smaller 65 refractory tube provided with air apertures

about its exterior circumference, a liquid fuel steam atomizing nozzle in said last named casing aligned with the axis of the smaller refractory tube, a U shaped pipe, closed at each end, and secured to each side 70 of the exterior refractory casing entering the combustion chamber and supported above the trough, a water spray nozzle in one end thereof, a connection from the other end thereof to the steam atomizing nozzle, a 75 source of liquid fuel connected to the fuel nozzle, and a source of water connected to the water spray nozzle.

6. A liquid fuel burning mechanism including means for delivering atomized fuel thereto, a refractory chamber in prolongation of the stream of atomized fuel into which said fuel enters, a surrounding refractory chamber having means for causing the fuel issuing from the first chamber to travel back 80 over the walls of the first chamber, said surrounding chamber having discharge nozzles about its surface through which a portion of the fuel passes for burning in the atmosphere, a third refractory chamber having 85 means communicating with the first chamber adjacent the fuel delivery thereto and having a refractory passage leading thereinto from the second chamber, and means for admitting atmospheric air to the third chamber 90 adjacent the said communicating means.

7. A liquid fuel burning mechanism including means for delivering atomized fuel thereto, an elongated refractory chamber in prolongation of the flow of atomized fuel into which said fuel enters, a refractory chamber surrounding said first chamber having a closed end spaced apart from the end of the first chamber most distant from the entrance of the fuel causing the fuel issuing from the first chamber to travel back over the walls of the first chamber, said surrounding chamber having discharge apertures provided about its upper surface through which a portion of the fuel passes for burning in the atmosphere, a third refractory chamber arranged at an angle to said first chamber and communicating with said first chamber adjacent the fuel delivery thereto, a refractory passage leading from between the spaced apart walls 100 of the first and second chambers to the end of the third chamber most distant from the delivery fuel and means for admitting atmospheric air to the third chamber adjacent to the said passage and at a distance from said discharge apertures in the walls of the second chamber.

WALTER W. WILLIAMS.
